UNITED STATES PATENT OFFICE.

JAMES F. WELCH, OF BROOKLYN, AND ERNST F. AUTENRIETH, OF NEW YORK, ASSIGNORS TO THE GLEN COVE MACHINE COMPANY, (LIMITED,) OF GREEN POINT, BROOKLYN, NEW YORK.

FEEDING DEVICE FOR PLANING-MACHINES.

SPECIFICATION forming part of Letters Patent No. 401,524, dated April 16, 1889.

Application filed November 27, 1888. Serial No. 291,961. (No model.)

To all whom it may concern:-

Be it known that we, JAMES F. WELCH, of Brooklyn, (Green Point,) in the county of Kings and State of New York, and ERNST F. AUTEN-
5 RIETH, of New York, in the county and State of New York, have invented a new and useful Improvement in Feeding Devices for Planing-Machines, of which the following is a specification.

10 We will describe in detail portions of a planing-machine embodying our improvement, and then point out the novel features in claims.

15 In the accompanying drawings, Figure 1 is a plan or top view of a planing-machine embodying our improvement. Fig. 2 is a longitudinal section taken on the line $x-x$, Fig. 1. Fig. 3 is a vertical section taken on the line $y-y$, Fig. 1. Fig. 4 is a detailed vertical section 20 taken on the line $z-z$, Fig. 1.

Similar letters of reference designate corresponding parts in all the figures.

25 We have only illustrated such parts of a planing-machine as are essential to an understanding of our invention. In these, A designates the frame of the machine.

30 B designates a shaft upon which is a pulley, a , by which motion is transmitted to the shaft. This shaft is journaled in suitable bearings in the frame A, and has formed upon it at intervals throughout its length worms a' . These worms gear with worm-wheels a^2 , mounted upon the lower end of upright shafts or spindles a^3 , journaled in suitable bearings in horizontally-extending portions a^4 of the frame. Upon the ends of the shafts or spindles a^3 are mounted vertically-extending presser-rollers a^5 . When the shaft B is rotated, rotary motion is imparted to the rollers a^5 , whereby a board 35 passing between them will be guided and its forward movement will be assisted. We have shown this machine organized to feed forward a number of boards at a time. For this reason we have shown three pairs of the presser-
40 rollers a^5 , the rollers being arranged in two rows. Near the other end of the shaft B there is mounted upon it a sprocket-wheel, b . A sprocket-chain, b' , transmits motion from the sprocket-wheel b to a sprocket-wheel, b^2 , 45 mounted upon a horizontally-extending shaft,

b^3 . Upon the shaft b^3 are rigidly secured a number of rotary disks b^4 . We have shown but three of such disks, but we may use any desired number, according to the number of boards which it is desired to pass through the machine. The rotation of these disks operates to feed a board forward by its frictional contact with the board. Upon the shaft b^3 there is also mounted a sprocket-wheel, b^5 , from which motion is transmitted by means of a sprocket-chain, b^6 , to a sprocket-wheel, b^7 , mounted upon a horizontally-extending shaft, b^8 . Upon the shaft b^8 are rigidly mounted rotary disks b^9 . The disks b^9 are in line with the disks b^4 and the shafts b^3 and b^8 , and consequently all of the disks rotate in unison. 55 60 65 70

We desire to place a number of boards together to be successively fed forward, and which will be successively brought into contact with the rotary feeding-disks b^4 b^9 . 75 We have shown three boards adapted to be successively brought into contact with each of the disks b^4 b^9 . Each of the sets of three boards, having been placed upon the shafts b^3 b^8 , is moved forward until the two boards farthest from the adjacent feed-disks b^4 b^9 80 85 90 95 100

In Fig. 4 it is shown more clearly that the shaft b^11 at intervals throughout its length is screw-threaded. These screw-threads engage nuts b^{12} , extending downwardly from the stops b^{10} . By rotating the shaft b^{11} , as shown, by means of a hand-wheel, b^{13} , the stops b^{10} may be moved horizontally in unison. This is for the purpose of accommodating boards of different widths. The stops are maintained in a vertical position by means of a rectangularly-shaped bar, b^{14} , extending between the side portions of the frame and through suitable apertures in the stops, so that the stops may slide upon the bar.

It will be seen that but one board is in contact with each of the feed-disks b^4 b^9 at a time. The other boards of each set are maintained firmly against the one in contact with the feed-disks, and the latter firmly against the said disks by means of yielding pressers D. These

yielding pressers are here shown as fingers mounted near their rear ends upon upwardly-extending pins or studs d , which latter extend upwardly from a cross bar or plate, D' . The 5 pressers D are vertically adjustable on the pins or studs d , and are maintained in any position into which they may be adjusted by set-screws d' . The pins or studs d extend loosely through apertures in the cross bar or 10 plate D' , and are free to turn therein. Upon their lower ends in the example of improvement shown are rigidly mounted horizontally-extending arms, d^2 , which are below the cross bar or plate D' . The arms d^2 , together with 15 collars d^3 on the pins or studs d above the cross bar or plate D' , prevent vertical displacement of the pins or studs.

Secured to the outer ends of the arms d^2 are 20 cords or chains d^4 , which cords or chains extend for a distance horizontally and then pass over pulleys d^5 , mounted upon pins or studs d^6 , extending from the cross bar or plate D' . Suspended by the cords or chains d^4 are weights 25 d^7 . These weights operate to so rock the pins or studs d as to cause the pressers D to press firmly, and yet with a sliding pressure, against 30 the outer board of the set. Of course, instead of using weights to effect this operation of the pressers, springs might be employed or the pressers themselves might be made resilient.

A machine having been set in motion, the 35 board of each set in contact with the feeding-disks b^4 b^9 is fed forward by said disks and between the presser-rollers a^5 , the other boards of the set being maintained against forward movement by the stops b^{10} . When the boards next the feeding-disks have been fed past them and the presser-rollers have drawn the 40 same past the stops b^{10} , the pressers D operate to force other boards quickly and firmly into contact with the feeding-disks b^4 b^9 . It will therefore be seen that a large number of boards may be placed in the machine at one

time, and that the same will be automatically 45 set forward one after another.

It will be seen that all the feeding-disks rotate in vertical planes and have their faces contacting with the board to drive it. It will also be seen that the yielding pressers are independent of the feeding-disks. 50

What we claim as our invention, and desire to secure by Letters Patent, is—

1. In a planing-machine, the combination, with rotary shafts, of feeding-disks mounted 55 on said shafts so as to rotate in vertical planes and having their faces contacting with the board to be fed, and yielding pressers independent of said disks operating to force the board into contact with the disks, substantially as specified. 60

2. In a planing-machine, the combination, with rotary shafts, of feeding-disks mounted on said shafts so as to rotate in vertical planes and having their faces contacting with the 65 board to be fed, yielding pressers adapted to maintain a number of boards in contact with each other and one of said boards in contact with the feeding-disks, and a stop for preventing a forward movement of any of the 70 boards except the one in contact with the feeding-disks, substantially as specified.

3. In a planing-machine, the combination, with rotary shafts, of feeding-disks mounted 75 on said shafts so as to rotate in vertical planes and having their faces contacting with the board to be fed, yielding pressers adapted to maintain a number of boards in contact with each other and one of said boards in contact with the feeding-disks, and an adjustable stop 80 for preventing a forward movement of any of the boards except the one in contact with the feeding-disks, substantially as specified.

JAMES F. WELCH.
ERNST F. AUTENRIETH.
